UNITED STATES PATENT OFFICE

HENRI HENNEBUTTE AND EDOUARD GOUTAL, OF PARIS, FRANCE, ASSIGNORS TO SO-CIÉTÉ ANONYME "LA CARBONITE" OF ST. DENIS-SUR-SEINE, FRANCE, A COMPANY OF FRANCE

TAR-SEPARATING APPARATUS

Application filed November 28, 1927, Serial No. 236,347, and in France December 2, 1926.

The first classification of the gasified products obtained during the operations of carbonizing wood, peat, lignite etc. (and the like), has for its object to obtain a separation which is as complete as possible between the vapors condensable at the ordinary temperature and the gases which are not condensable in these conditions.

Apparatus are used for this purpose in which the mixture of gas and vapor, when in contact with suitable surfaces which are artificially cooled, is subjected to a reduction of temperature such that it will more or less completely give up the condensable vapors, such as the tars and water vapor whilst on the other hand the gases properly so called are discharged.

This operation, which requires large heat exchanging surfaces in apparatus of great size, and very active cooling processes, for instance the use of large quantities of cold water, has been rendered more effective by the use of washing or bubbling methods making it possible more completely to collect the vapors by means of suitable solvents.

For such purposes, various arrangements have been devised in which the liquid products in greater or less quantities are placed in contact with the vaporized products which are to be condensed.

The present invention has for its object an apparatus for the application of the methods based upon this last-mentioned principle.

The said apparatus will assure, with a small expenditure of power, an energetic stirring of the material already liquefied and the gasified products to be separated, so that when operating for instance at about 100 degrees C. there will be obtained an absolute separation between the water vapor and the permanent gases on the one hand, and the condensable products on the other hand.

The apparatus comprises a receptacle within which the hot gases to be separated are brought into a tapered vessel having a movement of rapid rotation on its axis, and coaxial with a second tapered vessel which is stationary and has the peripheral position. The condensed products collect at the bottom of said receptacle and are mixed up by stirring devices

mounted on the rotary tapered vessel. The said products are finally withdrawn through curved pipes which conduct them above the central region of the rotary tapered vessel, whence they descend into the mass. We utilize in this manner the triple action of the centrifugal force produced by the rotation of the tapered vessel, of the entraining and the stirring by the stirring members mounted on the said tapered vessel, and of the circulation in a closed circuit in the curved tubes.

The following description, with reference to the appended drawings which are given by way of example, show the manner in which the invention may be carried into effect.

Figs. 1 and 2 represent respectively in vertical section and in horizontal section, the apparatus according to the invention.

A receptacle 1 of small volume and of special form is placed in the insulating casing 2; it is supplied by the conduit 3 with the current of hot gases whose condensable vapors are to be retained. The said conduit which is extended in the form of a tapered vessel 4 contains a second tapered vessel 5 with flaring bottom part, which is mounted on a shaft 6 and is given a movement of rotation at variable speeds by means of the pulleys 7 and 8 actuated by belting or by other means. Upon the internal walls of the rotary tapered vessel 5 are mounted the blades or stirrers 9 whose form is such as to provide for the stirring and mixing of the liquid mass and the gaseous products contained in the receptacle 1, which stirring, combined with the effect of the rotation of the tapered vessel produces a sort of emulsion of the liquid and the gaseous substances which are thus placed in close contact.

Upon the walls of the receptacle 1 are mounted the curved tubes 10 which may be provided in any suitable number and whose ends are immersed in the mass of liquid in such manner that this moving mass will be taken up by said tubes and will be continually discharged into the middle part of the apparatus through the medium of the inclined planes 14, whilst the uncondensable gases will be evacuated through the conduit 15.

A pipe 16, whose discharge can be regulated.

by overflow, serves to maintain a constant level for the condensed liquid in the interior of the apparatus.

5 A pressure-gauge 17 serves as an indicator for regulating the speed of rotation so as to obtain the suction or vacuum which may be desired.

The said apparatus effects a very complete separation between the gases and the vapors.

10 The tar will for instance be entirely condensed, whilst the fixed gases and the water vapor will be drawn off, if care is taken to operate at a sufficiently high temperature. It will constitute an excellent separator for the tar in carbonizing apparatus, and chiefly in sets of portable furnaces operating in forests in which sources of cooling water are entirely absent.

15 It is obvious that modifications may be made in the construction of the said apparatus, without departing from the principle of the present invention.

20 In this manner the principle of the apparatus may be extended so as to comprise the separation of gases from vapors in widely differing circumstances.

25 What we claim is:

30 1. A separator for gases and condensable vapors, more especially applicable to the classification of the gasified products obtained in the course of the carbonization of wood, peat, lignite, etc., and comprising a receptacle, a conduit for the gasified products leading to the central part of said receptacle, 35 a rotary member in this conduit, vanes on said rotary member for stirring the liquid in the receptacle, and curved tubes having their inlet ends at the lower part of the receptacle and their outlets at a higher level above said 40 rotary member and adapted to circulate the liquid material contained in said receptacle.

45 2. An apparatus for the purpose specified, comprising in combination a receptacle for the materials to be separated, a conduit terminating in a truncated cone whereby said materials are brought to the middle part of said receptacle, a second truncated cone rotatably supported within the first and provided with blades for stirring said materials, and curved pipes having their inlets near the bottom of said receptacle and their outlets at a higher level and opening towards the center of the receptacle and adapted to circulate the liquid material contained in said 50 receptacle.

55 In testimony whereof we have signed this specification.

HENRI HENNEBUTTE.
EDOUARD GOUTAL.
